United States Patent Office.

JOHN SCANLAN, OF CHICAGO, ILLINOIS.

Letters Patent No. 70,029, dated October 22, 1867; antedated October 16, 1867.

IMPROVEMENT IN ROOFING-FABRIC.

The Schedule referred to in these Letters Patent and making part of the same.

TO ALL WHOM IT MAY CONCERN:

Be it known that I, JOHN SCANLAN, of Chicago, in the county of Cook, and State of Illinois, have invented a new and useful Improvement in Felt-Roofing; and I do hereby declare and make known that the following is a full, clear, and exact description of the same, reference being had to the accompanying drawings, and the letters and figures marked thereon, which form part of this specification.

To enable those skilled in the art to understand how to construct and use my invention, I will proceed to describe the same with particularity, making reference in so doing to the aforesaid drawings, in which—

Figure 1 represents a plan or top view of my invention as arranged in strips upon the roof, and

Figure 2 is a section of one of said strips, showing the different layers composing the same, and their arrangement with each other.

Similar letters of reference in the different figures of the drawings denote the same parts of my invention.

A represents different layers of the roofing as arranged upon a roof; the material being manufactured in strips of any desired length, and applied as shown, extending across the roof in a manner corresponding with the arrangement of the layers of shingles upon a shingled roof. Each layer or strip of the roofing is composed of three layers or thicknesses of felt, or its equivalent, prepared in the manner hereinafter described. The lower stratum consists of dry felt *a*, which is designed to lie upon the roof-boards, and is used in a dry state, to prevent its adhering to the boards, as, in case of adhesion, there would be great danger of injuring the roofing by the shrinking of the roof-boards, which would crack it and cause it to leak. The next stratum *b* is composed of felt which has been thoroughly saturated in coal tar, or its equivalent, and afterwards coated with or passed through a melted water-proof composition. Upon this is arranged another layer of felt, saturated with coal tar, and these three layers, being substantially of the same width, are arranged as shown with respect to each other, so as to form a thin edge to the strip for convenience in overlapping one strip upon another. The three layers are then passed through between suitable pressing-rollers, or other pressing apparatus, which press the whole compactly and firmly together, forming rolls of any desired width or length ready for transportation.

This roofing can be applied readily by any one, arranging the layers as shown and specified, and securing them to the roof in any suitable manner. The ordinary gravel coat may be applied upon this roofing after being laid upon the roof, if desired.

Having described the construction of my invention, and the manner of applying the same, I will now specify what I claim, and desire to secure by Letters Patent:

I claim, as a new article of manufacture, roofing composed of two layers of saturated felt and one layer of dry felt, arranged as and for the purposes specified.

JOHN SCANLAN.
